METHOD OF FORMING MULTIPLE PATTERNS

Raymond J. Miller, Detroit, Mich., assignor, by direct and mesne assignments, to Miller Engineering Corporation, Detroit, Mich., a corporation of Michigan

Application November 11, 1942, Serial No. 465,234

7 Claims. (Cl. 22—191)

This invention relates to patterns and more particularly to the making of multiple pattern equipment for use where a plurality of identical castings are to be formed in a single flask.

Heretofore three principal methods have been employed in the formation of multiple pattern equipment where a large number of castings are desired of a size such that a plurality of castings may be formed in a single flask. (1) The formation of a plurality of castings from a master pattern embodying double shrinkage and finishing allowances. These castings are machined and hand finished to embody the shape and contour of the desired article to be formed and include single shrinkage and finish allowances. (2) The machining and hand finishing from solid blocks of metal of a desired number of separate pattern segments conforming to the contour of the article to be formed and including single shrinkage and finish allowances. (3) The use of a number of master patterns secured to a gate, and these patterns and gate members used in a casting operation to form production pattern equipment.

These pattern segments are attached in any suitable manner to a plate to provide the desired multiple pattern equipment. In both these methods great difficulties have been encountered, particularly in the formation of patterns of articles of unsymmetrical contour where patterns of vertically-spaced portions of the article to be cast must be provided to form cooperating mold impressions in the cope and drag sections of the flask.

The completed pattern segments must be accurately aligned vertically and in two dimensions horizontally on opposite sides of a single plate where a matched plate pattern is produced, or must be aligned accurately vertically and in two dimensions horizontally where the cooperating pattern segments are carried by separate plates to form the desired cooperating mold impressions. If the pattern segments are not properly aligned, the vertical edges of the mold cavities in the cope and drag sections of the flask will not align accurately and defective castings will result. In view of these complications the cost and time required to make multiple pattern equipment has been undesirably high.

Because of the human error involved in machining and hand finishing a large number of separate pattern segments accurately in three dimensions and endeavoring to align them in two dimensions horizontally on plates with a sufficient degree of accuracy for use in casting opera-

tions, it has been virtually impossible to form multipattern equipment of articles of complicated contours or shapes.

An object of this invention is to form multiple pattern equipment by a reproductive process from identical impressions of a single master pattern.

Another object of the invention resides in the provision of a novel method whereby multiple patterns may be quickly and accurately formed by a reproductive process from a master pattern.

A further object of the invention resides in the provision of an improved method whereby multiple pattern equipment, either of the matched plate or the single plate or dissociated type, may be readily formed by a reproductive process from a master pattern of any suitable material.

Still another object of the invention resides in the provision of an improved method of accurately locating cooperating pattern segments on opposite sides of a single plate where matched plate patterns are employed or on separate plates where simple plate patterns are used for casting purposes.

Another object is to provide a multiple pattern-forming mold having a plurality of spaced segments each having mold cavities formed from a master pattern by a reproductive process and bonded together in such a manner as to provide accurately located mold impressions.

Still a further object resides in the provision of an improved method of locating multiple pattern-forming mold cavities relative to each other by forming a plurality of blocks having impressions of a master pattern and locator means and positioning these blocks on correspondingly spaced locator means.

Yet another object is to provide multiple pattern equipment by a reproductive process from a plurality of accurately-spaced mold impressions of a single master pattern.

A further object is to provide matched multiple pattern equipment formed by introducing into accurately spaced mold impressions of a master pattern a moldable substance capable of completely filling the mold impressions and accurately conforming to the contour thereof.

Still a further object of this invention resides in the accurate positioning of a plurality of pattern impressions on a plate having locating means spaced correspondingly with locating impressions associated with the pattern impressions.

A further object resides in the provision of means for bonding together a plurality of pattern-impression-carrying blocks formed from a master pattern and accurately located on a plate

to provide a female impression of multiple pattern equipment of a desired predetermined external size.

Still another object of this invention is to provide production multiple-pattern equipment formed by a reproductive process wherein impressions of locator means associated with a master pattern being reproduced are transferred to a plurality of mold impressions of the master pattern to accurately locate the mold impressions on a plate having locating means spaced correspondingly with the impressions of the locating means associated with the impressions of the master pattern.

Yet a further object is to provide multiple production pattern equipment including feeding runners by a reproduction process.

Another object of the invention is to form matched plate patterns by interposing a pattern-carrying frame between vertically-spaced mold impressions of the article to be reproduced and filling the space within the frame and between the mold impressions with a moldable substance capable of filling and accurately conforming to the contour of the mold impressions.

A further object resides in the formation of multiple pattern equipment from identical female impressions of a pattern and locator means formed by spraying molten alloy or metal directly onto the surface of the pattern and locator means.

Another object of the invention is to provide an improved method of forming multiple molds for making multiple wax patterns for use in the so-called disappearing wax method of casting.

Other objects and advantages of this invention will be apparent from the following detailed description considered in connection with the accompanying drawings, submitted for purposes of illustration only, and not intended to define the scope of the invention, reference being had for that purpose to the subjoined claims.

In the drawings wherein similar reference characters refer to similar parts throughout the several views:

Fig. 1 is a plan view of a split master pattern or model of any article to be reproduced.

Fig. 2 is an end elevation of the pattern illustrated in Fig. 1.

Fig. 3 is a side elevation thereof.

Fig. 4 illustrates the pattern equipment of Figs. 1 to 3 mounted on opposite sides of a pattern-carrying plate.

Fig. 5 is an enlarged sectional view of the pattern illustrated in Fig. 4 showing a locator in place.

Fig. 6 is a plan view of the pattern equipment illustrated in Fig. 5.

Fig. 7 is a sectional view corresponding to Fig. 5 showing the formation of a block having an impression of the exposed portion of one of the pattern segments and of the locator.

Fig. 8 is a sectional view similar to Fig. 7 showing a modification of the method of forming a block having an impression of the pattern segment and locator means.

Fig. 9 illustrates the positioning of a plurality of pattern impression-carrying blocks on a plate provided with locating means spaced to correspond with the spacing of the locator means in the impression-carrying blocks.

Fig. 10 is a sectional view taken substantially on the staggered line 10—10 of Fig. 9 looking in the direction of the arrows.

Fig. 11 is a sectional view showing the bonding

of the pattern impression-carrying blocks of Figs. 9 and 10 into a single pattern impression body.

Fig. 12 is a fragmentary sectional view similar to Fig. 11 showing the bonding together of the pattern impression-carrying blocks of Fig. 8 into a single pattern impression body.

Fig. 13 is a plan view of the multiple pattern impressions of Fig. 9 showing the gate and feeder-forming impressions.

Fig. 14 is a sectional view taken substantially on the staggered line 14—14 of Fig. 13 looking in the direction of the arrows and showing the formation of the production multiple pattern equipment from the pattern impressions illustrated in Figs. 11 and 13.

Fig. 15 is a perspective view of a completed one-half of a production die pattern equipment.

Fig. 16 is a longitudinal sectional view showing several sets of production die patterns of Fig. 13 mounted in a flask.

Fig. 17 is a sectional view illustrating a modified form of the invention wherein multiple production pattern equipment is formed from a unitary master pattern and showing the step of embedding the pattern and locating means in any suitable parting material.

Fig. 18 is a sectional view illustrating the step of forming an impression of the exposed portion of the unitary pattern and locating means.

Fig. 19 is also a sectional view illustrating the step of removing the parting material and forming the reciprocal impression of the unitary pattern and locator members.

Fig. 20 is a fragmentary longitudinal sectional view illustrating the formation of matched plate production pattern equipment from vertically spaced mold impressions of the master pattern bonded together after having been located by means of locator pins.

Fig. 21 is a fragmentary sectional view illustrating the method of forming matched plate pattern equipment having a wide pattern parting plate.

Fig. 22 is a plan view of the embodiment illustrated in Fig. 21 and illustrating the step of aligning the pattern impressions with the pattern parting plate.

Fig. 23 is a perspective view of the completed matched plate production pattern equipment illustrated in Fig. 18.

Fig. 24 is a fragmentary sectional view illustrating the use of the multiple pattern impression molds in the formation of wax patterns for use in the so-called disappearing wax method of casting.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Referring now to the drawings, Figs. 1 to 3 are illustrative of a master pattern 10 of any article which may be formed by a casting operation. The article to be cast need not be symmetrical, yet preferably but not necessarily embodies a straight parting line. The pattern 10 may, for example, be formed of wood or any other suitable substance and may be of the split type having cope and drag sections 12 and 14 to form mold impressions in the cope and drag sections respectively of a mold.

The article to be cast may, for example, be an

anchor-shaped article having spaced bosses 16 and 18 interconnected by angularly-extending spaced rib members 20. Outwardly-directed projections 22 carried by the boss 16 terminate in flukes 24.

In the formation of multiple production pattern equipment from the master pattern 10, the upper and lower sections 12 and 14 may be attached to opposite sides of a small plate 26 and accurately aligned with each other by means of pins 28 and 30 extending through holes drilled through aligned portions of the pattern segments 12 and 14. At the time these holes are drilled the pattern segments should be accurately aligned with each other in order to locate them accurately on opposite sides of the plate 26. The ends of the aligning and attaching pins 28 and 30 may be smoothed off with reference to the surface of the pattern members so as not to interfere with the contour of the article being reproduced.

The pattern segments 12 and 14 are thus located accurately vertically and in two dimensions horizontally on opposite sides of the plate 26. It will be apparent that other means of locating and attaching the pattern segments on opposite sides of the plate 26 may be employed; for example they may be aligned and fastened to the plate by cementing, soldering, brazing, etc.

Apertures may be formed in the completed casting by providing kiss-through extensions in the mold-forming substance by providing apertures or cut-out portions in the cooperating pattern members. If apertures are desired in a casting without the use of the kiss-through extensions in the mold-forming substance, the locating and attaching pins 28 and 30 may project through the aperture-forming cutouts in the pattern members, and the pins 28 and 30 may be punch marked to reproduce on the casting a seat to locate a drill.

In the use of my improved method of making multiple production pattern equipment, a plurality of impressions of the cope and drag sections 12 and 14 of the pattern 10 are formed in a substance possessing the characteristics of accurately conforming to the contour of the pattern and hardening or solidifying.

In view of the fact that the cope and drag sections 12 and 14 of the pattern 10 are accurately aligned on opposite sides of the plate 26 by means of the pins 28 and 30, it is only necessary to provide locating means to accurately position the cope and drag pattern impressions with reference to each other to insure the formation of accurately aligned pattern impressions.

One desirable form of such locating means comprises locating pins 32 and 34 extending through the plate 26 and spaced from the pattern segments 12 and 14. The distance between the locating pins may be chosen arbitrarily, but it is preferably an even dimension which may be readily reproduced, as by locating the apertures in the plate by means of a template. The pins 32 and 34 are preferably tapered outwardly from a point adjacent the surface of the plate 26 to eliminate back draft and to facilitate the removal of moldable substance therefrom.

Impressions of the cope and drag pattern segments and the cooperating locator means may then be formed in the moldable substance with assurance that when the cope and drag locator means are properly aligned with reference to each other, the impressions of the cope and drag pattern segments will be accurately aligned with each other.

After the cope and drag segments 12 and 14

5 of the pattern 10 and locating pins 32 and 34 have thus been secured to the plate 26, a frame 36 may be positioned on the plate 26 to surround the upper segment 12 of the pattern 10 and the locating pins 32 and 34. Moldable substance may then be introduced into the space within the frame 36 to form a block 38 having a female impression of the pattern segment 12 and the locating pins 32 and 34. After the block 38 of the moldable substance has solidified or attained a predetermined set, the block 38 having the pattern and locating impressions therein may be removed from the plate 26 and frame 36.

10 The moldable substance of which the block 38 is formed may be any substance capable of flowing and hardening under temperature and pressure conditions not injurious to the surface of the material of which the pattern 10 is formed and preferably embodying substantially constant volume upon change of state from liquid to solid.

15 Suitable materials for this purpose are the various woods or type metal, white metal, plaster of Paris, or dental plaster, the Cerro alloys such for example as cerrobend, an alloy possessing the characteristic of flowing at approximately 160° and solidifying with negligible change of volume, and cerrobase, possessing the characteristic of flowing at approximately 350° F., being also desirable.

20 After a number of blocks 38 having female pattern and locating impressions therein corresponding with the number of pattern members desired in the completed multiple pattern equipment have been formed, the plate 26 may be inverted. The frame 36 may then be placed on the opposite side of the plate 26 to surround the drag pattern segment 14, and the ends of the locating pins 32 and 34 project outwardly from that side of the plate 26. A corresponding number of blocks having female impressions of the pattern segment 14 and locator pins 32 and 34 may then be formed. If desired a plurality of frames 36 may be employed and the blocks 38 may remain in the frames.

25 Fig. 8 illustrates a modified form of the invention wherein an impression of the pattern and locating means is formed in a block 39 of an alloy or metal. The block 39 is preferably formed by spraying any suitable alloy or metal onto the exposed surface of the pattern and locator members. The spraying operation is continued until approximately $\frac{1}{16}$ " of alloy or metal has been built up around the pattern and locator members and the exposed surface of the plate 26. If desired, a frame may be positioned around the pattern and locator members to confine the outer periphery of the block 39, or the outer edges of the block 39 may be cut away in any suitable manner to provide a block 39 having small marginal edges extending beyond the contour of the pattern and locator members. Where the block 39 is formed of a low melting temperature alloy it is desirable that the sprayed material be applied rather rapidly to prevent buckling.

30 A larger plate 40 is provided with apertures to receive a plurality of sets of locating pins 42 and 44 corresponding in contour and spacing to the pins 32 and 34 of the plate 26. The locating pins receiving apertures may be accurately located in the plate 40 by means of the same template plate used to locate the apertures for the locating pins 32 and 34 in the plate 26 on a jig borer may be employed to accurately locate the spacing of the apertures in the plate 40. The pins 42 and 44

project through the plate 40 and are preferably of the same size and embody the same exposed tapered contour as the locating pins 32 and 34 positioned in the plate 26.

The frame 36 is preferably shaped to conform rather closely to the exposed contours of the cope and drag pattern segments 12 and 14 and the locator pins 32 and 34 employed in horizontally locating the spaced portions of the pattern 10 vertically relative to each other to permit the positioning of a large number of pattern-impression carrying blocks 38 or 39 on the larger plate 40. If the blocks 38 or 39 do not closely conform to the shape of the pattern and locating pins, the excess material of the blocks 38 disposed outside of the impressions of the pattern and locating members may be removed by any convenient cutting or machining operation.

The blocks 38 or 39 having the impressions of the pattern and locator means may be positioned on the plate 40 with the pattern impressions directed towards the surface of the plate 40 and the locator pins 42 and 44 of the plate 40 projecting into the impressions of the locator pins 32 and 34 in the blocks 38 or 39.

In view of the fact that the blocks 38 or 39 have small marginal surfaces extending outside the contour of the pattern and locator means carried by the plate 26, the pattern impressions may be closely spaced on the plate 40, and a relatively large number of identical pattern impressions may be positioned on the plate 40.

The locating pins 32 and 34 may be positioned closely adjacent to the contour of the pattern segments, since it is necessary only that they be spaced apart to accurately position the pattern impressions in a predetermined relation on the plate 40. If desired, a single locator member having a contoured surface such as an extended cylindrical member having a pointed side may be employed rather than the spaced pins 32 and 34. The individual pattern impressions of the multiple pattern equipment will therefore be closely spaced to assure economical use of the mold space in casting operations.

The plate 40 should preferably have an external dimension corresponding to that of a standard flask to permit the formation of multiple pattern equipment readily adaptable for use in molding operations.

Where special molding equipment is employed, such for example as in the "Capaco" process of plaster molding where a plurality of pattern-carrying blocks of accurate external dimensions are fitted into a flask to form a die pattern, the plate 40 should preferably accurately conform with the external dimensions of one of the pattern-carrying blocks.

In this process of molding, pattern-carrying blocks of a plurality of different sizes or of the same size may be positioned adjacent each other in a flask to form plaster molds embodying mold impressions of a plurality of pattern members positioned in a single flask. Plates 40 of different external dimensions may be employed to form patterns conforming to any desired external dimensions usable in this or other methods of casting.

After the blocks 38 or 39 have been positioned on the plate 40 as illustrated in Figs. 9 and 10, the plate 40 may be positioned on a drag pattern-forming frame 50 to clear the pins 40 and 42 as illustrated in Figs. 11 and 12 respectively. Where the pattern equipment being formed is to be used in casting operations similar to the so-called

Capaco process of plaster molding, the frame 50 is preferably machined to accurate external dimensions corresponding with the dimensions of a pattern block for use in the Capaco flask to form a die pattern. A cope pattern frame 52 of similar accurate external dimensions and contour is superimposed on the plate 40 to surround the blocks 38. The edges of the frame 52 and the plate 40 are then accurately aligned horizontally in two dimensions in a right-angle frame 54.

Any suitable moldable substance 56, such for example as Woods or type metal, white metal, plaster, or the Cerro alloys referred to above, or any suitable plastic material may be introduced into the space within the frame 52 to engage and securely lock the blocks 38 or 39 together and to the frame 52. The inwardly-extending bead 58 carried by the frame 52 projects into the substance 56 to securely bond the substance 56 and the blocks 38 or 39 to the frame 52 to form a female multiple pattern impression 60.

One of the female multiple impressions 60 or 62 may be cut away or contoured to provide an impression of a main feeding conduit 76, including impressions of branch conduits 78, leading to each of the pattern impressions of the article to be cast. Impressions of a surge pool 80 and a riser 82 communicating with the feeding conduit 76 may also be formed in the female multiple impression.

It will be apparent that, if desired, a gate tree having main and branch conduit impressions 76 and 78 and impressions of the surge pool 80 and riser 82 may be positioned on the plate 40 to communicate with the pattern impressions in the blocks 38 or 39 in the step illustrated in Figs. 9 and 10 before the substance 56 is applied in the step illustrated in Figs. 11 and 12 to securely bond the pattern impression-carrying blocks 38 or 39 together.

After the substance 56 has solidified or hardened, the frames 50 and 52 with the plate 40 interposed between them may be inverted. The blocks of moldable substance having the impressions of the drag pattern segments 14 and the locator means may then be applied to the exposed surface of the plate 40 within the drag pattern-forming frame 50, the impressions of the locator pins 32 and 34 fitting over the locating pins 42 and 44 of the plate 40 to accurately locate the drag pattern impressions relative to the cope pattern impressions vertically and in two horizontal dimensions. The frame 50 and the plate 40 should again be accurately aligned in the right-angle 54 and the blocks having the impressions of the drag pattern segments 14 bonded together and to the frame 50 in the manner previously indicated to form a female multiple impression 62 of the drag pattern segments 14 and locator means, illustrated in Fig. 18 and corresponding with the female multiple impression 60.

The female multiple cope and drag impressions 60 and 62 thus formed may be separated from the plate 40 and used, as illustrated in Fig. 14, to form production pattern equipment having impressions for the runner and feeder members.

The impressions of the locator means 32 and 34 formed in the blocks of the cope and drag female multiple impressions 60 and 62 may be filled before the production pattern equipment is formed as illustrated in Fig. 12. Any suitable substance may be employed for this purpose such for example as smooth-on, a metal compound, emery powder, plaster, or any of the Cerro alloys. It is desirable that a point of anchorage be pro-

vided to prevent the closure plugs from coming out of the apertures. This may be accomplished by running a drill hole in the walls of the apertures. Where the Cerro alloys are employed to fill the locating pin apertures, the hole may be poured full and a flat iron bar may be moved across the top of the aperture to level off the applied substance and to cause it to chill.

Where the pattern equipment is to be used in the so-called Capaco process of plaster molding a pattern-carrying frame 66 having accurate external horizontal and vertical dimensions conforming with the required dimensions of the pattern-carrying blocks of a die pattern is superimposed on the frame 52 and is accurately aligned therewith in two dimensions horizontally by means of the right angle 54. The frame 66 may be provided with internally threaded bosses 67 to facilitate attaching the pattern block to the flask to form a die pattern. A riser frame 68 conforming with the required horizontal dimensions of the pattern-carrying block is superimposed on the pattern-carrying frame 66 and is aligned therewith by means of the right angle 54. It will be obvious that a number of die patterns can be made from the same female impression. The use of the riser frame 68 in the making of production pattern equipment is more fully disclosed in my copending application Serial No. 454,831, filed August 14, 1942.

When the frames 52 and 66 have been properly aligned, a pattern-forming moldable substance 70 is introduced into the space within the frames 66 and 68 to fill the impressions of the pattern segments 12 in the female multiple impression 60 and to form a multiple production pattern 72 having a plurality of spaced pattern segments 74 accurately conforming with the shape and contour of the pattern segment 12 as illustrated in Fig. 15. Production pattern equipment accurately conforming to the shape and contour of the pattern segment 14 may be formed in a similar manner from the female multiple impression 62.

The pattern-forming moldable substance may be any suitable alloy or metal such for example as alloys of the Woods metal group, type metal, white metal, the Cerro alloys including cerrobend, cerrobase, cerromatrix, etc., or any suitable plastic material of the thermoplastic or thermosetting type.

To summarize the steps of accurately forming the cope and drag production pattern equipment it will be noted that the pattern segments 12 and 14 are accurately located relative to each other by the pins 28 and 30 extending through the plate 26. The impressions of these spaced pattern segments are accurately located relative to each other on their respective impression-carrying blocks by the impressions of the locator pins 32 and 34 projecting through the plate 26.

When the pattern impression-carrying blocks are mounted on the plate 40, the impressions of the pattern segments 12 and 14 are accurately located relative to each other in two dimensions horizontally by the locating pins 42 and 44 in the plate 40 and the pattern impressions are accurately located vertically by contact of the base of the impression-carrying blocks with the surface of the plate 40.

The impression-carrying blocks are accurately located relative to each other by alignment of the frames 52 and 50 with the edges of the plate 40 by means of the right angle 54, and the impression-carrying blocks are then bonded to-

gether and to their respective frames as illustrated in Figs. 11 and 12.

The pattern segments 14 of the production pattern equipment 72 are accurately located with reference to the edges of the frame 66 because of the alignment of the edges of the frame 66 with the edges of the frame 52 as illustrated in Fig. 14. The pattern segments of the production pattern equipment of the pattern segments 14 are correspondingly accurately aligned with reference to the edges of their corresponding frame or pattern plate. Assurance is thus had that the pattern segments of the cooperating pattern equipment will accurately align with each other to form accurately aligned mold impressions to produce good castings.

Where this pattern equipment is to be used in the so-called Capaco process of plaster molding, the production pattern 72 thus formed may be positioned in a flask 88 as illustrated in Fig. 16 to form a die pattern for the reception of a plaster molding substance to form cooperating cope and drag mold sections having impressions of the pattern segments 12 and 14 respectively for use in casting operations.

After the plaster or other mold-forming substance has attained a predetermined set in the flask 88, the mold is extracted from the pattern, and the mold is subjected to drying and curing operations whereby virtually all the moisture is dispelled from the mold to provide cooperating mold members having smooth, highly calendered surfaces accurately conforming to the contour of the pattern impressions. Molten alloy or metal may be poured directly into these mold impressions to form the desired castings. Due to the smooth, highly glazed surfaces of the mold impressions, castings having smooth surfaces accurately conforming to the contour of the pattern result, and in the majority of instances the castings may be used directly for industrial purposes without the necessity of additional machining operations.

Figs. 1 to 15 illustrate the formation of multiple production pattern equipment from split patterns wherein upper and lower sections 12 and 14 of the pattern equipment 10 are positioned on opposite sides of the plate 26, as in matched plate pattern practice. Figs. 17 to 19 illustrate the steps necessary in the formation of multiple production pattern equipment from a unitary pattern member 90.

The unitary pattern 90 is embedded in any suitable parting material 92 to a point 94 conforming to the natural parting line on the pattern. The parting material 92 may be any substance suitable for forming partings, such for example as molding clay, dental plaster, waxes of various types, plaster of Paris, et cetera.

After the pattern 90 has been embedded in the parting material 92 to the desired level, suitable locating means such as two locating pins 96 corresponding with the locating pins 32 and 34 illustrated in Figs. 5 to 7 are also embedded in the parting material 92. The locating pins 96 taper in opposite directions from a point 98 approximately midway of their length. The pins 96 are embedded in the parting material 92 up to the point 98 to eliminate back draft in the portions of the pins 96 embedded in the parting material and the exposed portions thereof.

After the pattern member 90 and the locating pins 96 have been embedded in the parting material 92, a frame 100 corresponding with the frame 36 illustrated in Fig. 7 may be positioned

to surround the pattern member and the locating pins. Any suitable moldable substance 102 may then be introduced into the space within the frame 100 to form a block having a female impression of the exposed portion of the pattern member 90, locating pins 96, and the parting material 92. These blocks corresponding with the blocks 38 or 39 formed in the step illustrated in Figs. 7 and 8 may be removed from the pattern and pattern and locating members 90 and 96 upon hardening or solidifying and used in the steps illustrated in Figs. 9 to 11 in the formation of multiple female impressions 60, each accurately conforming with the contour of the exposed portion of the pattern member 90 and locating members 96.

After a desired number of blocks having the desired pattern and locator impressions have been formed, they may be used, as illustrated in Figs. 9 to 14, in the formation of the desired production pattern equipment. One additional impression of the exposed portion of the pattern and locator means is formed, and the pattern is inverted as illustrated in Fig. 19 to rest on the frame 100. The parting material 92 applied in the step illustrated in Fig. 17 is then removed, and a frame 104 is superimposed on the frame 100. Moldable substance 106 is then introduced into the space within the frame 104 to form blocks having female impressions of the exposed portion of the pattern member 90, locating means 96, and the surface of the block 102 formed in the step illustrated in Fig. 18. Accurately matched impressions of vertically-spaced portions of the pattern member and locator means are thus formed from the unitary pattern member for use in making the desired production pattern equipment.

The multiple female impressions 60 and 62 formed in the steps illustrated in Figs. 1 to 10 and 15 to 17 may be used in the formation of matched plate pattern equipment.

As illustrated in Fig. 20 the plate 40 illustrated in Fig. 11 may be replaced by a frame 110 after the impression-carrying blocks have been bonded together as illustrated in Figs. 11 and 12. The frames 50 and 52 may be accurately aligned in two dimensions horizontally with the edges of the plate 110 by means of the right angle 54 as illustrated in Fig. 20. A feeding aperture 112 may be provided to supply molten alloy or metal to the space within the frame 110 and the pattern impressions carried by the multiple female impressions 60 and 62 to form a matched plate pattern having accurately-spaced pattern segments on opposite sides thereof as illustrated in Fig. 23.

If a matched plate pattern having a wide pattern plate is desired, the frame 110 of Fig. 20 may be dispensed with and a wide pattern frame 120 applied as illustrated in Figs. 21 and 22. The pattern plate 120 may be provided with a plurality of pins 122 as illustrated in Figs. 21 and 22 against which the edges of the frames 50 and 52 may abut to accurately align the female impressions in the multiple female members 60 and 62 horizontally in two directions with reference to each other and to the plate 120. The impressions of the cope and drag pattern members in the female multiple impressions 60 and 62 respectively are thus accurately aligned to form cope and drag pattern segments disposed on opposite sides of the plate 120. It will be apparent that the material of which the pattern is formed completely fills the space within the frame and between the

pattern impressions. This material engages on opposite sides of the contoured section 124 of the frame 120 to securely bond the pattern material to the frame 120.

5. If more durable or stronger pattern equipment is required than is afforded by the moldable substance 70 employed in the formation of production patterns, the multiple pattern equipment thus formed may be used as an intermediate step in the formation of production patterns of brass, bronze, aluminum, or any suitable high-strength alloy. When this expedient is resorted to the master pattern or model should embody double shrinkage allowance.

10. The multiple production pattern 72 formed by the reproductive process set out above may be employed in the so-called Capaco method of plaster molding to form production pattern equipment of suitable alloys or substances. In view of 20 the accuracy of casting operations by the so-called Capaco process, it is only necessary that approximately .002" be provided for finishing the production high-strength pattern equipment.

15. The multiple production pattern equipment 72 or the multiple match plate pattern of Figs. 20 to 23 may also be used in the formation of dies for plastic molding operations where great hardness is required. Alloys such for example as Beryllium copper having a hardness factor in excess of 387 Brinell are now available for use in this manner.

20. The female multiple pattern-forming molds 60 and 62 may be assembled as illustrated in Fig. 24 and used in the formation of wax patterns for use in the so-called disappearing wax method of 35 forming castings. Where the multiple molds 60 and 62 are used in this manner, a locator member such for example as a dowel pin 130 may be employed at each end to locate the mold members 60 and 62 relative to each other. The dowel pins 130 may be located in position at the time the substance 56 is applied to bond together the impression-carrying blocks 38 or 39. Main and branch-feeding conduits 132 and 134 respectively may be 40 provided to admit the wax to the pattern molds to form the desired multiple wax patterns.

25. Plastic materials either of the thermoplastic or thermosetting types may be employed in the formation of the blocks carrying the female impressions or in the formation of the production pattern equipment desired.

I claim:

1. The method of making multiple production patterns comprising securing a master pattern to a plate, positioning locating pins on the plate, forming a plurality of separate blocks each having a female impression of the pattern and recesses for the locating pins, providing a larger plate with a plurality of sets of locating pins, locating a plurality of blocks on the larger plate, and aligning the recesses with the locating pins, bonding the separate blocks together to form a multiple pattern mold, and forming a production pattern from the multiple pattern mold.

5. The method of forming multiple pattern equipment from a master split pattern comprising aligning the cope and drag pattern segments on opposite sides of a plate and attaching them thereto, projecting aligning means through the 60 plate adjacent the pattern segments, forming a plurality of blocks having impressions of the cope and drag pattern segments and aligning means, positioning a plurality of said blocks on opposite sides of a larger plate having similar aligning means to accurately locate the impressions of the

cope and drag pattern segments on opposite sides of the larger plate, positioning frames around the blocks having the impressions of the cope and drag pattern segments, aligning the edges of the frames and plate, bonding said blocks to their respective frames to form multiple female impressions of the cope and drag pattern segments, and forming multiple cope and drag patterns from the cope and drag multiple female impressions.

3. The method of forming multiple pattern equipment from a unitary master pattern comprising embedding said pattern in parting material to divide the pattern into cope and drag sections and to eliminate back draft, embedding aligning means in the parting material adjacent the pattern and to eliminate back draft, forming a plurality of blocks having impressions of the cope and drag pattern sections and aligning means, positioning a plurality of said blocks on opposite sides of a larger plate having similar aligning means to accurately locate the impressions of the cope and drag pattern segments on opposite sides of the larger plate, positioning frames around the blocks having the impressions of the cope and drag pattern, aligning the edges of the frames and plate, bonding said blocks to their respective frames to form multiple female impressions of the cope and drag pattern segments, and forming multiple cope and drag patterns from the cope and drag multiple female impressions.

4. The method of forming molds for making multiple production patterns comprising securing master pattern segments on opposite sides of a plate, positioning locating means adjacent the pattern segments, forming a plurality of separate blocks each having a female impression of a pattern segment and an impression of the locating means, providing a larger plate with a plurality of locating means, locating a plurality of blocks on the larger plate and aligning the impressions of the locating means on the locating means of the larger plate, and bonding the separate blocks together to form a multiple pattern mold.

5. The method of making match plate production pattern equipment comprising forming mold

blocks having impressions of vertically-spaced portions of a master pattern and impressions of spaced locator members, locating impressions of vertically-spaced pattern portions in spaced alignment by aligning impressions of locator members with similarly positioned locator members carried by a flat plate, bonding the blocks together on the flat plate to form molds having a plurality of female impressions of the master pattern, and forming production match plate pattern equipment from the molds having said multiple female impressions.

6. The method of forming matching cope and drag multiple production patterns comprising forming a plurality of blocks having female impressions of spaced portions of a master pattern and impressions of spaced locator means, positioning said blocks on a plate having locator means with the impressions of the locator means in the blocks on the locator means of the plate to locate the cope and drag mold cavities of the blocks in spaced alignment, bonding said blocks together to form cope and drag molds each having a plurality of identical impressions of the spaced portions of the master pattern, and forming production patterns from said molds.

7. The method of making a matched plate multiple pattern from a unitary master pattern, comprising forming a plurality of blocks having cope and drag impressions of spaced portions of the master pattern and impressions of spaced locator means, successively positioning the cope and drag impressions of spaced portions of the pattern on opposite sides of a plate having similarly spaced locator means projecting therethrough to locate the cope and drag impressions of the pattern relative to each other, bonding the impression-carrying blocks together to form cope and drag molds each having a plurality of aligned female impressions of the spaced portions of the master pattern, positioning a frame between the cope and drag molds, and forming the matched plate multiple pattern by introducing a moldable substance into said pattern impressions and frame.

RAYMOND J. MILLER.
